CABINET

John T. Armbruster, Niagara Falls, N. Y., assignor
to American Optical Company, Southbridge,
Mass., a voluntary association of Massachusetts

Application November 15, 1952, Serial No. 22,314

Term of patent 14 years

(Cl. D33—19)

To all whom it may concern:

Be it known that I, John T. Armbruster, a citizen of the United States of America, residing at Niagara Falls, in the county of Niagara, and State of New York, have invented a new, original, and ornamental Design for a Cabinet, of which the following is a specification, reference being made to the accompanying drawing forming a part thereof.

In the drawing:

Fig. 1 is a perspective view of a cabinet, showing my new design;

Fig. 2 is a perspective view of the cabinet similar to Fig. 1 but showing the cover sections and one door open and the drawer extended; and

Fig. 3 is a side elevational view showing the opposite side of the cabinet.

The characteristic features of the new design reside in the portions shown in full lines in the drawing.

I claim:

The ornamental design for a cabinet, substantially as shown and described.

JOHN T. ARMBRUSTER.
